CLAIM

The ornamental design for a desk, as shown and described.

DESCRIPTION

FIG. 1 is a front, top and right-side perspective view of a desk showing my new design;
FIG. 2 is a front, bottom, and right-side perspective view thereof;

FIG. 3 is a front view thereof;

FIG. 4 is a rear view thereof;

FIG. 5 is a top view thereof;

FIG. 6 is a bottom view thereof;

FIG. 7 is a right-side view thereof;

FIG. 8 is a left-side view thereof; and,

FIG. 9 is a front, top and right-side perspective view shown with the desk in a lowered position, with environmental structure.

The broken lines illustrating a shelf shown in FIG. 9 represent environmental structure that forms no part of the claimed design. The remaining broken lines in FIGS. 1-4 and 6-9 represent portions of the desk that form no part of the claimed design.

1 Claim, 9 Drawing Sheets
